(57) **CLAIM**

The ornamental design for a walk-through detector, as shown and described.

DESCRIPTION

The present application is a continuation-in-part of U.S. patent application Ser. No. 16/456,808, filed Jun. 28, 2019, entitled Walk-Through Detector Systems and Methods, the entire disclosure of which is incorporated herein by reference. Although not part of the currently claimed design, aspects and embodiments of the designs of the Walk-Through Detectors shown in said prior U.S. Patent Application are incorporated into this present application as though included herein in full.

FIGS. 1-7 show a first embodiment of a walk-through detector, wherein:

FIG. 1 is a perspective view from a top-front-right direction of the first embodiment;

FIG. 2 is a rear view of the first embodiment;

FIG. 3 is a front view of the first embodiment;

FIG. 4 is a left side view of the first embodiment;

FIG. 5 is a right side view of the first embodiment;

FIG. 6 is a top view of the first embodiment, wherein a front side of the walk-through detector faces a top side of the figure;

FIG. 7 is a bottom view of the first embodiment, wherein a front side of the walk-through detector faces a top side of the figure.

FIGS. 8-10 show embodiments of a display screen of a walk-through detector, wherein:

FIG. 8 shows a display screen of a walk-through detector in an off state;

FIG. 9 shows the display screen of a walk-through detector of FIG. 8 in a walk-through state; and,

FIG. 10 shows the display screen of a walk-through detector of FIG. 8 in a do not walk-through state.
